United States Patent Office.

TOBIAS J. KINDLEBERGER, OF EATON, OHIO.

Letters Patent No. 63,058, dated March 19, 1867.

IMPROVEMENT IN WATER-WHEELS.

The Schedule referred to in these Letters Patent and making part of the same.

TO ALL WHOM IT MAY CONCERN:

Be it known that I, TOBIAS J. KINDLEBERGER, of Eaton, in the county of Preble, and State of Ohio, have invented certain new and useful Improvements in Water-Wheels; and I do hereby declare that the following is a clear, full, and exact description thereof, reference being had to the accompanying drawings, making part of this specification, and to the letters of reference marked thereon, like letters indicating like parts wherever they occur.

My invention consists in certain improvements upon the wheel patented to me July 11, 1865, and has relation to the devices for closing the gates, the form of the buckets, and the step for supporting the wheel.

Figure 1 is a plan view of the case.

Figure 2, a vertical section of the shaft and rims or flanges of the wheel.

Figure 3, a side view of the wheel; and

Figures 4, 5, 6, and 7, views of portions in detail.

The body of the wheel in this case is made in the manner described in the patent heretofore alluded to, and consists of a crown plate, I, secured rigidly to the shaft G, and two circular rims, I', placed at equal distances apart, below the plate I, as shown in fig. 2. These plates I' are horizontal for one-fourth of their width from the outer edge, from whence they incline downward and inward at an angle of thirty-two degrees, as shown in fig. 2, the crown plate I being fashioned to correspond therewith. Between these plates are placed the buckets d, as represented in fig. 3. These buckets d consist of oblong metallic plates, having their outer edges inclined at an angle of twenty degrees from a perpendicular, as indicated in fig. 3. For one-fourth of the width of the plates I', that is to say, when the buckets are in contact with the horizontal portion of the plates, the buckets are curved so as to present a concave surface near the periphery of the wheel, as represented in fig. 4, which is a plan view of a portion of the rim and buckets, looking from below on the line xx of fig. 3, and thus showing the buckets reversed. From the point where the rim or plate I' begins to incline downward the bucket d begins to curve in the opposite direction, and from thence to its inner end presents a convex surface, it being at the same time slightly twisted, so that its inner end approaches very nearly to a vertical or upright position. These buckets are located alternately at equal distances apart, between the rims, as represented in fig. 3. The wheel, thus constructed, is enclosed in a metallic case, consisting of a top plate, B, and an annular rim, A, at the bottom, as represented in fig. 1, those being the same as in my former patent, except that the top plate B has its outer edge notched, as shown in fig. 1, to permit the arms of the gates to close or lie therein, while the protruding points of the plate B extend out even with the edge of rim A, thus permitting the case to be rolled over, when moving, without danger of breaking the arms r of the gates H, as no weight can be thrown on them. The plates H, fig. 6, are arranged in a series between the plates A and B, in such a manner as to surround the wheel, as in my former case. These gates are cast with flanges on their backs, for the double purpose of strengthening them, and also to form bearings for the bolt t, upon which they are pivoted. An arm, r, projects from the upper rear corner of the gate, as represented in figs. 6 and 5, by which it is attached to the closing devices. These devices consist of a plate, C, resting above the plate B, and turning loosely around the shaft G, and having an arm, D, projecting from one side, with a segmental rack on its outer end, as shown in fig. 1. Into this rack a worm-wheel, E, gears, the latter being operated by a bevel-gear on its end engaging with a similar wheel secured to the lower end of a vertical shaft, to the top of which is attached the hand-wheel F, the arrangement of the gear being shown in fig. 7. To this plate C a rod, a, is pivoted, and is connected at its outer end (by devices shown in fig. 5) with the arm r of the gate, so that, by turning the hand-wheel F, the gates may be closed or opened at will. It however frequently happens that a stick or other obstruction may accidentally get into one of the openings between the gates, and thus prevent one of the gates from closing. In order to provide for such a contingency, I do not attach the rod a directly to the gate, but to a hollow box, b, where it is held by a spiral spring, m, as represented in fig. 5. This box b is cast hollow, to receive the spring, its rear end being closed by means of a plate, c, which is cast in the form shown, to fit to the box b, and its arm or prolongation, which is attached or pivoted by the bolt l to the arm r of the gate H, the bolt l being held in place by a pin or key, i. The bolt a has a circular head fitting the interior of the box b, and serving to compress the spring m. A set-screw, o, is inserted through the plate C, with its end pressing

against the head of bolt o , so that, by adjusting this screw o , all the gates may be adjusted to shut precisely alike. If any obstruction should interfere with the closing of any of the gates, the spring m attached thereto will yield, and permit all the other gates to be closed, while that remains open. In order to permit the arrangement of the rods a to be reversed, as is necessary to adapt the gates to a wheel having its buckets reversed, their inner end is pivoted to a rim placed directly under the plate C , and attached rigidly thereto. To the under side of plate C a bent lug, n , is secured, as represented in fig. 1, it being so arranged that when the rod a stands inclined either to the right or the left the lug n will be directly over the rod, and thus prevent it from becoming unhooked. At the same time, by turning the rod a in a radial position, it will be brought from under the lug n , and can then be hooked or unhooked at will. The gates are pivoted on a bolt, t , as shown in fig. 6, and this bolt is held in place by a key, u , which is fitted into a notch or recess on the rear side of said bolt, and being held between the bolt and the outer face of the bucket, so that, by simply removing the key u , the bolt can be withdrawn and the gate taken out and replaced at will. I provide for the step on which my wheel is to run a wooden block or pin, as represented by h of fig. 2. This pin h I perforate with one or more transverse holes, connected with another vertical hole terminating at its apex, as shown in fig. 2. This pin or step h I then surround with a funnel-shaped dish or receptacle, x . This dish and step being located at the bottom of the wheel, will thus be kept always wet, the dish being filled with water, which, entering the holes formed in the step, will always keep it well lubricated and cool.

The general plan and operation of the wheel being similar to that hereinbefore referred to, need not be further described.

Having thus described my improvements, what I claim, is—

1. The wheel, having its plates and their buckets constructed and arranged as herein described.
2. The combination and arrangement of the plate C , arm D , worm-wheel E , and bevel-gear, with hand-wheel F , for operating the gates, as set forth.
3. The combination of the rod a , box b , and spiral spring m , with the set-screw o , arranged to operate as and for the purpose set forth.
4. I claim constructing the crown plate B , with the recesses or notches in its periphery, as shown and described, the outer points of said plate being arranged to protrude even with the periphery of the annular rim A , as and for the purpose herein set forth.
5. I claim constructing the gate H , with the outwardly projecting arm r , for the purpose of attaching the spring box b thereto, as shown and described.

T. J. KINDLEBERGER.
